United States Patent Office

Des. 193,695
Patented Sept. 25, 1962

193,695

SEWING MACHINE BED OR SIMILAR ARTICLE

Walter D. Szuba, Westfield, and Edward A. Bruder, Roselle, N.J., assignors to The Singer Manufacturing Company, Elizabeth, N.J., a corporation of New Jersey

Filed June 15, 1961, Ser. No. 65,610

Term of patent 14 years

(Cl. D70—2)

Fig. 1

Fig. 2

Fig.3

Fig.4

Fig.5

Fig.7

Fig.6

FIG. 1 is a front perspective view of a sewing machine bed, showing our new design,

FIG. 2 is a rear perspective view thereof, on a reduced scale,

FIG. 3 is a reduced scale top plan view thereof,

FIG. 4 is a reduced scale front elevational view,

FIG. 5 is a reduced scale right side elevational view,

FIG. 6 is a reduced scale left side elevational view, and

FIG. 7 is a reduced scale bottom plan view.

The broken-line showing of the sewing machine head in FIGS. 1 and 2 is for illustrative purposes only.

We claim:

The ornamental design for a sewing machine bed or similar article, substantially as shown and described.
